UNITED STATES PATENT OFFICE.

JOHN J. TATUM, OF BALTIMORE, MARYLAND, ASSIGNOR, BY MESNE ASSIGNMENTS,
TO F. H. MURPHY COMPANY, OF PARNASSUS, PENNSYLVANIA, A CORPORATION OF
PENNSYLVANIA.

CAR-ROOF.

1,239,740.

Specification of Letters Patent. Patented Sept. 11, 1917.

Application filed January 8, 1913. Serial No. 740,777.

To all whom it may concern:

Be it known that I, JOHN J. TATUM, a citizen of the United States, residing in the city of Baltimore, in the State of Maryland, 5 have invented certain new and useful Improvements in Car-Roofs, of which the following is a specification.

It is a well known fact that the roof sheets of outside metal car roofs have a back and forth movement relatively to the body of the car when the car is in motion. This movement is called "weaving" and is greatest in a direction lengthwise of the car. As a result of such movement of the roof sheets 10 the running board saddle, which commonly rests on the roof sheets, but which is bolted fast to the substructure of the roof, wears off the protective covering of paint and ultimately rusts holes in the roof sheets near 15 the ridge of the roof. A fracture of the roof sheet at that point, through which rain, snow and dust may pass into the interior of the car, is concealed by the running board saddles and is likely to remain unobserved 20 until the lading in the car is damaged, thus resulting in claims for damages against the railroads. Furthermore, a sheet thus worn at the ridge end is a total loss, as it must be thrown away, notwithstanding the balance 25 30 of its area is uninjured.

The principal object of my invention is to arrange the roof sheets upon the car in such way as to eliminate all liability of the main roof sheets becoming damaged by chafing of 35 the running board saddles. Further objects are to provide means for securing the roof sheets loosely along both their eaves and ridge margins, and to reduce the cost of maintenance and cost of repairs of car roofs 40 to a minimum. With these and other objects in view my invention consists in the novel parts and combinations of parts hereinafter described; and is more fully pointed out in the claims.

45 In the drawing:

Figure 1 is a transverse section and perspective view of the top portion of a car on which my improved roof is applied;

Fig. 2 is an enlarged transverse section 50 view at the ridge of the car through the ridge sheet and inner end portion of two roofing sheets, showing the joint between them;

Fig. 3 is an enlarged transverse sectional 55 view at the eaves of the car, showing the

joint between the eaves flashing strip and outer end of a roofing sheet;

Fig. 4 is a sectional view through two roofing sheets, showing the flexible watertight seam or joint between them; 60

Fig. 5 is an enlarged perspective view of the running board saddle and end cap, showing portions of the running boards, the roof sheets and the ridge sheet in their respective positions relative thereto; 65

Fig. 6 is a side elevation of the parts shown in Fig. 5;

Fig. 7 is a perspective view of the running board saddle cap; and

Fig. 8 is a top plan view of the running 70 board saddle and its end caps.

For the purpose of illustrating and describing my improved roof, I have shown it applied to a car having side posts 1, side sheathing 2 and side plates 3. The roof 75 substructure comprises the carlines 4, the wooden roof sheathing 5 and the fascia boards 6 which are secured on the side sheathing at the eaves of the car and which have their lower edges thickened to protect 80 the roof sheets and flashing from side swiping and cornering.

The main roofing sheets 7, which are not as long as the standard roofing sheet now in use, are rebent along their outer or eaves 85 ends into parallel planes on their under sides to form hooked flanges 8, the edges 9 of which are doubled under and terminate back from the eaves of the car as more clearly seen in Fig. 3. The doubled edges of the 90 flanges space the latter above the eaves flashing, and act as water sheds to direct water and dirt toward the eaves of the car instead of its catching in the pockets formed by the hooked flanges. 95

Metal flashing strips 10 are nailed at one edge to the fascia 6, thence bent over the eaves to cover the joint between the side sheathing and side plate and may extend a short distance onto the roof sheathing 5. A 100 portion 11 along the inner margin of the flashing is doubled back above the main body of the flashing to form a hooked flange and its edge 12 is doubled in the same manner as the edges of the roof sheet flanges. 105 The flashing is hooked into the flanges on the eaves ends of the roof sheets and secures them loosely upon the car along the eaves line. The doubled edges 9 and 12 prevent moisture and dirt from "creeping" along the 110

flashing and roof sheets and also act as spacing members between the sheets and flashing. It will be noted that the joint between the roof sheets and the flashing is short of the eaves of the car and that the roof sheets are thereby protected from injury by side-swiping.

The side marginal edges of the roof sheets are flanged up and rebent, as shown in Fig. 4, so as to interlock and form a flexible watertight joint or seam between adjacent sheets.

The ridge or inner ends of the main roof sheets are rebent into parallel planes spaced above the sheets to form hooked flanges 13, the edges of which are doubled under to form water sheds 14. The ridge roof sheet 15 extends from end to end of the car either in a single strip or preferably in overlapping sections. It is bent up intermediate its ends to form transverse inverted channel shaped hoods 16 which register with and straddle the flexible seams of the side marginal edges of the roof sheets, said hoods being of greater inside width than said marginal seams whereby the seams may move freely within the hoods when the roof is distorted or the roof sheets are weaving.

The longitudinal margins of the ridge roof sheet 15 are rebent into planes parallel to and under the adjacent portions thereof, forming hooked flanges 17. The edges 18 of these flanges are doubled under as shown in Fig. 2. The flanges 13 on the inner ends of the roof sheets hook into and interlock with the marginal flanges of the ridge sheets, thereby forming a flexible watertight joint between the roof sheets 7 and the ridge roof sheet 15. It is evident that the main roof sheets 7 can move crosswise and lengthwise on the roof substructure when the car is weaving without subjecting the sheets 7 to strain or buckling, as they have flexible joints at their side marginal edges and at their eaves and ridge ends. In other words, the sheets 7 are free to float on the roof substructure but at the same time they are securely fastened to the car.

The running board saddles 19 are arranged on top of the ridge roof sheet 15 over the hoods 16, each being provided with a longitudinal groove in which said hood enters. The end spaces between the sides of the hoods 16 and the flexible seams 21 of the main roof sheets are closed against entrance of water and cinders by means of hood caps 22. This hood cap is provided with side wings 23 having openings 24 in which are fixed the ends of a bolt 25 passing through the end of the running board saddle, thereby loosely securing the hood cap to the end of the running board saddle. The lower edges of the caps extend below the saddles in close proximity to the roofing sheets 7, and are pro-

vided with notches 26 constructed to fit 65 snugly over the seams 21 of said roof sheets. The hood caps and bolts 25 are free to slide with the roof sheets 7 transversely of the ends of the saddles, thereby enabling them to have a snug fit with the seams 21, and 70 maintaining the tight closure of the open ends of the hoods 16.

As shown in the drawings the length of the saddle 19 is equal to the width of the ridge roof sheet 15, and it is supported 75 thereon and does not come in contact with the main roof sheets 7. The running board saddles 19 carry the running boards 20 and are rigidly secured to the car at the ridge in any well known manner.

A car roof embodying my invention is flexible at the ridge as well as at the eaves and there is no liability of the running board saddle cutting through the main roof sheets, whereby the life of the roof is materially prolonged.

The possibility of the running board saddles cutting through the ridge roof sheets is extremely remote as there is practically no relative movement between them; however 90 should this happen repairs can be made quickly and at a small expense as compared with the expense of replacing the relatively wide and long main roof sheets 7, inasmuch as it would only be necessary to replace the 95 comparatively narrow ridge roof sheets 15.

Although I have illustrated and described what I consider to be the best form of my invention, I do not desire to limit myself thereto, as it is evident that modifications 100 may be made in the constructional details thereof.

What I claim is:

1. A car roof including separate roof sheets terminating short of the eaves and short of the ridge, a ridge sheet secured upon the substructure at the ridge and extending beyond each side of the ridge, said ridge sheet having undeturned flanges along its side margins, loosely interlocking 110 with the ridge end of the roof sheet, said flanges limiting the movement of the roof sheets from the ridge, and means movably connecting the eaves ends of the roof sheets to the roof substructure, whereby the roof 115 sheets are limited as to endwise movement away from the eaves and are free to move sidewise and diagonally at both top and bottom ends at the same time, when the car body is weaving.

2. A car roof comprising a series of main roof sheets having hook shape end flanges, flexible seams connecting said sheets at their side marginal edges, eaves flashing strips having hook shape flanges engaging said sheets at 125 the eaves ends thereof to loosely secure them upon the roof substructure, and a ridge sheet having hook shape flanges engaging

the hook shaped ridge flanges of said main roof sheets at the ridge ends thereof and secured to the substructure whereby the main roof sheets are limited as to endwise 5 movement toward the eaves and are free to move sidewise and diagonally at both eaves and ridge ends at the same time, when the car is weaving.

3. In a car roof the combination with a 10 series of movable roof sheets connected together at their side marginal edges by upstanding flexible seams, of a fixed ridge roof sheet extending longitudinally of the car and covering the ridge ends of said movable sheets, hoods formed in said ridge sheet over the seams of the movable roof sheets and of greater transverse dimension than the 15 transverse dimension of said seams, running board saddles positioned over said hoods and attached to the car, and caps fitting over said seams and closing the spaces between the side walls of the hoods and the seams, said caps being slidably mounted on the ends 20

of said saddles whereby they may move longitudinally with said seams. 25

4. In a car roof the combination with a running board saddle, of a cap slidably mounted on the end of the saddle and provided with a notch constructed to receive a roof seam with which it interlocks. 30

5. In a car roof, the combination of transverse roof sheets connected by upstanding side marginal seams, a roof sheet extending along the ridge, running board saddles supported on said ridge roof sheet, said running board saddles having grooves in their under sides adapted to embrace said upstanding seams, and caps loosely mounted on the ends of said running board saddles covering the 35 ends of said grooves. 40

Signed at city of Baltimore, this 21st day of November, 1912.

JOHN J. TATUM.
